Charles W. Sharp

INVENTOR

BY *E. M. Bond*
ATTORNEY

UNITED STATES PATENT OFFICE.

CHARLES WESLEY SHARP, OF HAMILTON, ONTARIO, CANADA.

NONREFILLABLE BOTTLE.

Application filed August 9, 1920. Serial No. 402,245.

To all whom it may concern:

Be it known that I, CHARLES W. SHARP, a citizen of the Dominion of Canada, residing at Hamilton, in the county of Wentworth and Province of Ontario, have invented certain new and useful Improvements in Nonrefillable Bottles, of which the following is a specification.

This invention relates to a bottle which when filled and corked cannot be tampered with without breaking the neck thereof.

The object of my invention is to provide a bottle in which the cork is locked against tampering with until it is desired to open the bottle.

A further object is to provide a bottle by which customers will at once know as to whether it has been refilled or whether it is the original filling from the user of the bottle.

With these and other objects in view, the invention consists in the construction, combination and arrangements of parts as will be hereinafter fully described, illustrated in the accompanying drawings, and pointed out in the claim hereunto appended.

Figure 1 is a sectional view of my invention after it has been corked and sealed by the original users, and

Fig. 2 is a corresponding sectional view in which is illustrated the neck of the bottle after the seal has been broken.

Referring to the drawings like numerals designate like parts in the various drawings.

3 is a bottle made of glass or any similar material which is used to form containers for liquids and which are molded into shape. This bottle may be of any desired shape or size but is provided with a neck 4 which is preferably annular in cross section but may be of any particular shape desired. In molding this neck an extension 5 is formed which leaves a small groove 6 interiorly of the lower end of the extension 5 and exteriorly of the upper portion of the neck 4. In this groove I provide a ring of rubber or any other suitable packing 7, the purpose of which will hereinafter

be mentioned. The extension 5 is attached to the neck by a much thinner material section as at 8 than the thickness of either the neck or the extension.

If desired the extension may be provided at opposite sides with outwardly extending portions 9 in which is positioned openings on the interior of the extension as at 10. 11 is a cork having an annular top to fit over the upper side of the extension 5. The body portion 12 of the cork extends down interiorly of the extension 5 and is provided with a transverse opening as at 14. Positioned inside this transverse opening when desired, corking the bottle up is a coil spring 15 and locking pins 16.

After the bottle has been filled, a cork 17 is positioned interiorly of the neck as indicated in the drawings. The spring with the locking pins 16 is then pressed inward into the transverse opening 14 and the body of the seal or cork 11 is pushed into the extension 5. When pressed down so that the transverse opening 14 registers opposite the openings 10, the locking pins 16 will be tensioned outward so that their outer ends will fit into these openings and thus lock the cork or seal against removal or further pressing downward. If desired, a ring 18 may be positioned between the upper side of the extension 5 and the under side of the annular top of the cork or seal 11.

When it is desirous to open the bottle, it will be necessary to press downward on the cork or seal 11 sufficient to break the connection 8 between the neck of the bottle 4 and the extension 5. In breaking this the washer 6 prevents any glass splintering over the cork 17. The cork 17 then can be pulled in the ordinary manner and if desired the extension 5 may be used as indicated in Fig. 2 or can be dispensed with.

From the foregoing it is thought that the construction of my invention will be clearly understood, and, therefore, a more extended explanation has been omitted.

What I claim as new is:

A container provided with a neck, an

extension formed from said neck, a much less resistant portion being between said neck and said extension, a packing ring between the upper portion of said neck and 5 the lower portion of said extension, a cork fitted into the upper end of said extension and a means for locking said cork against removal so that said portion must be broken

before the cork in said neck can be withdrawn.

10

In testimony whereof I affix my signature in the presence of two witnesses.

CHARLES WESLEY SHARP.

Witnesses:

EVA TAYLOR,
MARTIN SIMON.
